[57] CLAIM

The ornamental design for a cryosurgical instrument, as shown and described.

DESCRIPTION

FIG. 1 is a perspective view of the cryosurgical instrument, with a rotatable valve operating lever in a first position.

FIG. 2 is a perspective view of the cryosurgical instrument of FIG. 1 with the valve operating lever in a second position.

FIG. 3 is a perspective view of the cryosurgical instrument of FIG. 1 with the valve operating lever in a third position; and,

The bottom surface of the cryosurgical instrument not shown in the drawing or described in the specification forms no part of the claimed design.

The undisclosed surfaces of the article not shown in the drawing are the same as the corresponding surfaces which are shown.
